US00D519500S

(12) **United States Design Patent** (10) Patent No.: **US D519,500 S**
Maskatia et al. (45) Date of Patent: **** Apr. 25, 2006**

(54) **PORTABLE ELECTRONIC DEVICE**

(75) Inventors: **Arif Maskatia**, San Jose, CA (US);
Stephen Cheung, San Jose, CA (US);
Kelly Kodama, San Jose, CA (US)

(73) Assignee: **ACER Inc. (TW)**

(**) Term: **14 Years**

(21) Appl. No.: **29/222,248**

(22) Filed: **Jan. 27, 2005**

(51) **LOC (8) Cl.** **14-02**

(52) **U.S. Cl.** **D14/318; D14/341**

(58) **Field of Classification Search** ..... **D14/315-323, D14/341-346; D18/1, 2, 7, 11; 235/145 A, 235/145 R; 341/22, 23; 345/156, 168, 169, 345/172, 173; 361/680-686; D19/26, 59, D19/60; 178/18.03; 434/307 R, 317, 308, 434/309; 349/12**

(57) **CLAIM**

The ornamental design for portable electronic device, as shown and described.

DESCRIPTION

FIG. 1 is a perspective view of portable electronic device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIGS. 8-11 are alternate perspective views thereof.
